UNITED STATES PATENT OFFICE.

EARL HENRY BEKKERING, OF DULUTH, MINNESOTA, ASSIGNOR TO DULUTH SHOW CASE COMPANY, OF DULUTH, MINNESOTA, A CORPORATION OF MINNESOTA.

ROCKING BIN.

1,264,258.

Specification of Letters Patent. Patented Apr. 30, 1918.

Application filed September 25, 1916. Serial No. 121,961.

To all whom it may concern:

Be it known that I, EARL HENRY BEKKERING, a citizen of the United States, residing at Duluth, in the county of St. Louis and 5 State of Minnesota, have invented certain new and useful Improvements in Rocking Bins, of which the following is a specification.

This invention relates to a rocking bin 10 and has for its object the provision of a receptacle of relatively large capacity so constructed and supported as to be balanced and therefore easily operable regardless of the quantity and weight of the material contained therein.

A further object of my invention is the provision of a rocking bin particularly adapted for use in connection with counters, shelving and the like and which provides 20 for ready access to the material contained within the bin.

Further objects and advantages of my invention will be apparent as it is better understood by reference to the following specification when read in connection with the accompanying drawing, illustrating the preferred embodiment thereof, in which—

Figure 1 is a vertical section through a counter and bin with the latter in closed 30 position, and

Fig. 2 is a similar view illustrating the open position of the bin.

Referring to the drawing, a counter is illustrated as comprising a top 1, front 2 and bottom 3. End or division walls 4 divide the space within the counter into compartments to receive one or more bins which are inserted and operate through openings in the rear of the counter, the rear walls of 40 the bins being adapted to close the openings when the bins are in closed position. The details of construction of the counter may be varied widely, my present invention residing more particularly in a bin of peculiar 45 construction and marked advantages over devices of a similar character now in common use.

The bin comprises a rear wall 5, side walls 6, and front wall 7 and bottom 8. The 50 walls and bottom may be constructed of any suitable material but preferably the rear and side walls 5 and 6 are of wood and the front wall 7 and bottom 8 of a continuous sheet of metal secured to the side walls 55 6. The rear wall 5 is flat and as previously

stated normally closes the opening to the compartment in which the bin is disposed. The upper edges of the side walls 6 are straight adjacent the rear wall 5 and curve downwardly at 9 as they approach the front 60 wall 7 to allow the bin to rock. The front lower corners of the side walls 6 are curved at 10 so that the front wall 7 and bottom 8 merge into each other, thus eliminating an angular corner. The bottom 8 bends upwardly at 11 to allow the bin to rock and provide for supporting the bin when in open 65 position.

A roller 12 is mounted in suitable brackets 13 secured to the bottom 8 adjacent the bend 70 11 therein. The roller 12 rests on a grooved metal plate 14 which is set into or fastened to the bottom 3 of the counter. This arrangement provides for a practically frictionless pivot for the bin while permitting 75 the bin to be bodily removed from and replaced in the counter at will. A handle 15 is secured to the rear wall 5 of the bin.

The mode of operation of my improved bin will be apparent from the following 80 brief description thereof. The bin may be cleaned if necessary after removing it bodily from the counter. The removal is accomplished as readily as the removal of an ordinary drawer, no tools being required. 85 The bin is replaced with the roller 12 in engagement with the groove in the plate 14 and is filled with the desired quantity of material. To close or open the bin the operator grasps the handle 15 and rocks the bin 90 toward or from the counter. When in open or closed position the center of gravity is on the corresponding side of the plane normal to the bottom 3 of the counter at the plate 14 and consequently the bin remains 95 indefinitely in open or closed position when so disposed. The arrangement is such, however, that a minimum of force is required to move the bin to either position.

Obviously various changes may be made 100 in the form, construction and arrangement of the parts without departing from the spirit and scope of the invention or sacrificing any of the material advantages thereof, the form hereinbefore described being 105 merely the preferred embodiment thereof.

I claim:

A storage receptacle comprising a casing forming a compartment having an opening at one end and a bottom elevated above the 110

surface upon which said receptacle rests, and a bin having a flat end forming a vertical closure for said opening when said bin is in closed position, a bottom disposed in 5 a plane substantially normal to said flat end adjacent the opposite end of said bin and upwardly directed adjacent said flat end to permit said bin to fulcrum at the junction of the normal and upwardly directed portions of said bottom, a roller secured to said 10 bottom at said junction and a plate secured

to the bottom of said casing and having a groove therein to receive said roller, said flat end extending below the upwardly directed portion of the bottom of said bin whereby 15 the space between said upwardly directed portion and the bottom of said casing is covered when said bin is in closed position.

EARL HENRY BEKKERING.
